UNIVERSAL CONNECTOR BLOCK FOR TELEPHONE FRAME EQUIPMENT

Paul V. De Luca, Port Washington, N.Y., assignor to
Porta Systems Corp., Syosset, N.Y.

Filed June 12, 1972, Ser. No. 262,139

Term of patent 14 years

Int. Cl. D14—08

U.S. Cl. D26—14 R

FIG. 1

FIG. 2

FIG. 3

FIG. 6

FIG. 4

FIG. 5

FIG. 1 is a top view of a universal connector block for telephone frame equipment embodying my new design, it being understood that the bottom is a mirror image thereof;

FIG. 2 is a front elevational view thereof;

FIG. 3 is a side elevational view thereof, it being understood that the opposite side is a mirror image of the side shown herein;

FIG. 4 is a rear elevational view thereof;

FIG. 5 is a sectional view thereof taken on the line 5—5 of FIG. 2; and

FIG. 6 is a sectional view of a universal connector block for telephone frame equipment showing a second embodiment of my new design which is taken on a line similar to 5—5 of FIG. 2, and wherein the difference resides in the arrangement of the pins.

The pattern of the pins and apertures shown at the top and bottom of the universal connector block in FIGS. 2 and 4 are understood to be continuous throughout its length.

I claim:

The ornamental design for a universal connector block for telephone frame equipment, substantially as shown and described.
